UNITED STATES PATENT OFFICE.

EDWARD A. JUDD, OF NEW BRITAIN, CONNECTICUT, ASSIGNOR TO THE CORBIN CABINET LOCK COMPANY, OF SAME PLACE.

DESIGN FOR A PADLOCK-CASE.

SPECIFICATION forming part of Design No. 21,821, dated August 30, 1892.

Application filed July 21, 1892. Serial No. 440,838. Term of patent 7 years.

To all whom it may concern:

Be it known that I, EDWARD A. JUDD, a citizen of the United States, residing at New Britain, in the county of Hartford and State of Connecticut, have invented and produced a new and original Design for Padlock-Cases, of which the following is a specification, reference being had to the accompanying drawing, showing my design.

10 The only figure of the drawing is a perspective view of a padlock, showing my design.

A designates the main portion of the case, which is substantially in the form of a rectangular box. B is a cylindrical portion at

the lower edge thereof, the length of the cylinder extending from side to side coincident with the lower edge of the main portion, thereby bringing the ends of the cylinder at the side edges of the box-like portion A. 20

C designates a shackle projecting from the upper end of the case, and D is the rotary hub in the cylindrical portion of the case.

What I claim is—

The design for a padlock-case, substantially 25 as shown and described.

EDWARD A. JUDD.
